G. Hume Talbert

Attorney

UNITED STATES PATENT OFFICE.

PAUL CAMPBELL, OF SAN ANTONIO, TEXAS.

CLOTHESPIN.

Application filed May 16, 1922. Serial No. 561,395.

To all whom it may concern:

Be it known that PAUL CAMPBELL, a citizen of the United States of America, residing at San Antonio, in the county of Bexar and State of Texas, has invented new and useful Improvements in Clothespins, of which the following is a specification.

The object of the invention is to provide a simple and inexpensive metallic clothes pin which may be left permanently connected with the line for convenience and accessibility when required; and with this object in view the invention consists in a construction and combination of parts of 15 which a preferred embodiment is shown in the accompanying drawings, wherein:

Figure 1 is a view of a clothes pin embodying the invention applied in the operative position to the line.

20 Figure 2 is a similar view showing the pin in the inoperative or inactive position on the line.

Figures 3, 4, 5 and 6 are views respectively of opposite sides and opposite edges 25 of the pin.

The pin is constructed of a single blank of resilient wire which is doubled upon itself and coiled to form the combined grip and spring eye 10 from which extend side 30 strands 11 and 12 which are doubled upon themselves to form loops constituting opposed jaws which are yieldingly impelled toward each other by the spring tendency of the coil. The looped ends of the jaws 35 are deflected as indicated at 13 to facilitate engagement with a line as indicated at 14 and also to pass readily over a fabric suspended on or extended over the line, and the free ends of the blank are arranged in 40 intersecting relation as indicated at 15 with the extremity of one member extended and deflected from the plane of the eye 10 to form a stud 16 constituting a directing finger whereby when the pin is not in use or 45 has been disengaged from the article of clothing which it has served to clamp on the line, may be used to direct the line into the loops forming the jaws,—the pin being inverted or reversed in position for this 50 purpose as indicated in Figure 2.

In other words the loops which consti-

tute the jaws serving to clamp an article of clothing on a line when the pin is in its normal or operative position serve as the means of suspending the pin on the line when the 55 article is not in use, the position of the pin when not in use being reversed from that in which it serves to clamp the article on the line so that the line may lie within the loops which constitute the jaws instead of between the jaws as when the pin is in use.

Having described the invention, what is claimed as new and useful is:—

1. A metallic clothes pin consisting of a single blank of wire doubled upon itself and 65 coiled at its center to form a spring eye and having its sides extended radially from the eye and looped to form opposing jaws which are spring impelled toward each other by the eye, with the terminal of one of the 70 sides angularly deflected from the plane of the eye to form an entrance throat to the loops constituting said jaws.

2. A metallic clothes pin consisting of a single blank of wire doubled upon itself 75 and coiled at its center to form a spring eye and having its sides extended radially from the eye and looped to form opposing jaws which are spring impelled toward each other by the eye, with the terminal of one of the 80 sides angularly deflected from the plane of the eye to form an entrance throat to the loops constituting said jaws, the extremities of the blank adjacent to said deflected terminal being disposed in inter- 85 cepting relation.

3. A metallic clothes pin consisting of a single blank of wire doubled upon itself and 90 coiled at its center to form a spring eye and having its sides extended radially from the eye and looped to form opposing jaws which are spring impelled toward each other by the eye, with the terminal of one of the sides angularly deflected from the 95 plane of the eye to form an entrance throat to the loops constituting said jaws, the closed ends of the loops forming the jaws being deflected to facilitate engagement with a line.

In testimony whereof he affixes his signature.

PAUL CAMPBELL.
